UNITED STATES PATENT OFFICE

2,269,271

LUGGAGE MANUFACTURE

Joseph Kiefer, Racine, Wis., assignor to Hartmann Trunk Company, Racine, Wis., a corporation of Wisconsin

Application October 3, 1938, Serial No. 232,981

2 Claims. (Cl. 190—41)

This invention relates to improvements in the art of luggage manufacture and more particularly to an improved wardrobe fixture construction and method of assembling the same.

Heretofore, in assembling garment folding frames, hanger supporting brackets, and cover stays in the cover, it has been common practice to drill a separate hole for each point of connection through side wall portions of the cover, and each hole had to be accurately located in a precise manner to insure proper operation of the fixtures with respects to one another and to insure proper positioning of the fixtures in the suitcase sections. In the type of garment fixture shown and described in Ritter Patent No. 1,975,292, there are supporting members or sockets for receiving the ends of the removable garment hanger unit, which require two rivets extending through each side wall; there is a garment folding frame having each end pivotally connected by a rivet; and there are cover stays similarly connected. As a result, each side wall of the cover must have four rivets extending therethrough, the heads of which are all exposed on the exterior of the suitcase. In addition, each one of these rivet points must be independently located in an accurate manner, which adds a substantial amount of time to the assembly operation. The present invention is adapted for use in expediting the assembly of various types of wardrobe fittings but is particularly adapted for use in connection with the type of construction shown in said prior patent.

It is therefore a general object of the invention to provide an improved construction for use in wardrobe luggage which decreases the number of rivets extending through the side walls of the cover.

A further object of the invention is to provide a construction, as above described, wherein the necessity of precisely locating each connecting point for the various fittings is eliminated, and wherein said fittings are connected through the medium of plates or brackets having preformed and accurately located apertures therein, whereby the fitting connections are necessarily suitably located when the brackets are in proper position.

A further object of the invention is to provide an improved method of assembling fittings in wardrobe luggage including the formation of apertures at predetermined positions in metal plates or brackets, the assembly of fittings on said plates through the use of some of said apertures,

and the subsequent assembly of the plates in the luggage.

Other objects of the invention are to provide a luggage fitting construction which is simple and inexpensive, which is easy to install, and which improves the appearance of the luggage by minimizing the number of exposed unsightly rivet heads.

With the above and other objects in view, the invention consists of the improvements in the art of luggage manufacture and all its parts and combinations as set forth in the claims and all equivalents thereof.

In the accompanying drawing, illustrating one complete embodiment of the preferred form of the invention, in which the same reference numerals designate the same parts in all of the views:

Fig. 1 is a front view of a wardrobe suitcase with the cover raised, the main body being shown in cross-section.

Fig. 2 is a perspective view on an enlarged scale of one of the metal plates or brackets.

Fig. 3 is a similar view showing fitting parts assembled thereon.

Fig. 4 is a fragmentary sectional view through an open suitcase showing one of the brackets and associated fittings installed; and

Fig. 5 is an enlarged sectional view taken on line 5—5 of Fig. 4, showing one end of the garment hanger member or unit.

Referring more particularly to the drawing, the numeral 6 designates the main body portion of a suitcase having a cover 7 hingedly connected thereto. The wardrobe fittings illustrated are the same as the fittings shown and described in Ritter Patent No. 1,975,292 except for the method of connection to the suitcase, which forms the subject matter of the present invention. These wardrobe fittings comprise generally a garment hanger member or carrier 8 for removably holding a plurality of individual garment hanger bars 9, said member having projecting lugs 10 at each end which are removably received in sockets or hanger supporting members 17. A substantially U-shaped garment folding frame 11 is also utilized, which frame comprises a transverse bar 12 and spaced side arms 13. Cover stays 14 are also utilized, as is standard practice, for the purpose of maintaining the cover in open position at a suitable angle to the main section.

Heretofore, it has been customary to secure each socket piece 17 directly to a side wall 15 of the cover by utilizing two rivets extending through the socket piece and having exposed heads on

the exterior of the suitcase. Similar rivets have been employed for connecting the inner ends of the side arms 13 of the garment folding frame to the wall 15, and additional rivets have been employed to pivotally connect ends of the cover stays 14 to the cover. Thus in former constructions there were four rivets extending through the side walls 15 of the cover to form unsightly exposed rivet heads on the exterior of the suitcase.

With the present invention brackets 16, preferably L-shaped, are preformed with precisely located apertures 18, 19, 20, 21, and 22 therein. These brackets may be simple metal stampings and, of course, there must be right and left hand brackets for the two sides of the case. In order to assemble the luggage fittings in the case, the inner ends of the side arms 13 of the garment frame 11 are pivotally connected to a pair of the brackets through the use of the aperture 19. A socket piece 17 is then secured to each bracket by means of two rivets extending through the openings 20 and 21.

The brackets and assembled fittings are then inserted in the suitcase and due to the fact that the brackets are angular in shape and fit in corners of the cover, they necessarily position themselves in the longitudinal direction of the cover side walls. It is only necessary, therefore, in installing the brackets to make sure that the distance a (Fig. 4) is proper. Each bracket may then be secured in position by a rivet 23 extending through the aperture 22 in the end wall of the cover and by a rivet 24 extending through the side wall 15. The last mentioned rivet is also employed to pivotally connect the upper end of the cover stay 14. Thus only two rivets extend through side walls of the cover, on each side thereof instead of the four which would otherwise be required. Furthermore, only one measurement is necessary in the installation whereas, with former methods of procedure, an accurate measurement in two directions had to be made for each one of the four connecting points heretofore required.

The construction and method are such that assembly is greatly facilitated and accuracy in assembly is assured.

Although the construction and method are particularly adapted for use in connection with the type of suitcase fittings illustrated, it is applicable to other similar fittings wherein the same problems of installation are involved.

Although only one form of the invention has been shown and described, it is obvious that various changes and modifications may be made without departing from the spirit of the invention and all of such changes are contemplated as may come within the scope of the claims.

What I claim is:

1. In combination, a suitcase comprising a main section and a cover section hinged thereto, said cover having side walls and a back wall, collapsible metal cover stays having ends pivotally connected to the main section and having

opposite ends extending adjacent the side walls of the cover, an elongated bracket positioned against each side wall of the cover to extend longitudinally of said wall, the outer end of each bracket having a cover stay pivot opening therein, a U-shaped garment supporting frame having its ends pivotally connected to said brackets below the cover stay pivot openings, a hanger supporting socket piece secured to each bracket with its bearing portion in substantial axial alignment with and offset inwardly of the suitcase from said pivotal connection for the garment frame, each bracket having a lower angularly bent apertured flange positioned against the back wall of the cover to positively locate the cover stay pivot opening of the bracket, the socket piece, and the pivotal connection for the garment frame a predetermined distance from the back wall of the cover along the adjacent side wall, means extending through the flange aperture of each bracket for securing the flange to the back wall of the cover, and means extending through the cover stays and through the cover stay pivot openings in the brackets for pivotally connecting the cover stays to the side walls of the cover and for also connecting the brackets to said side walls.

2. In combination, a suitcase comprising a main section and a cover section hinged thereto, said cover having side walls and a back wall, collapsible metal cover stays having ends pivotally connected to the main section and having opposite ends extending adjacent the side walls of the cover, an elongated bracket positioned against each side wall of the cover to extend longitudinally of said wall, the outer end of each bracket being curved laterally in the plane of the bracket and having a cover stay pivot opening therein, a U-shaped garment supporting frame having its ends pivotally connected to said brackets below the cover stay pivot openings, said pivotal connections for the garment supporting frame being offset inwardly away from the free edge of the cover side walls with respect to the cover stay pivot openings, a hanger supporting socket piece secured to each bracket with its bearing portion in substantial axial alignment with and offset inwardly of the suitcase from said pivotal connection for the garment frame, each bracket having a lower angularly bent apertured flange positioned against the back wall of the cover to positively locate the cover stay pivot opening of the bracket, the socket piece, and the pivotal connection for the garment frame a predetermined distance from the back wall of the cover along the adjacent side wall, means extending through the flange aperture of each bracket for securing the flange to the back wall of the cover, and means extending through the cover stays and through the cover stay pivot openings in the brackets for pivotally connecting the cover stays to the side walls of the cover and for also connecting the brackets to said side walls.

JOSEPH KIEFER.
